UNITED STATES PATENT OFFICE.

JOSEPH W. JONES, OF PHILADELPHIA, PENNSYLVANIA, ASSIGNOR TO HIMSELF AND JOSEPH A. VINCENT, OF SAME PLACE.

SOUND RECORDING AND REPRODUCING INSTRUMENT.

SPECIFICATION forming part of Letters Patent No. 600,815, dated March 8, 1898.

Application filed March 13, 1897. Serial No. 627,276. (No model.)

To all whom it may concern:

Be it known that I, JOSEPH W. JONES, a citizen of the United States, residing at Philadelphia, in the county of Philadelphia and 5 State of Pennsylvania, have invented certain new and useful Improvements in Sound Recording and Reproducing Instruments; and I do declare the following to be a full, clear, and exact description of the invention, such 10 as will enable others skilled in the art to which it appertains to make and use the same, reference being had to the accompanying drawings, and to the letters of reference marked thereon, which form a part of this specification. 15

My invention relates to new and useful improvements in sound recording and reproducing instruments, especially that class of instruments known as "gramophones," and 20 has for its object to provide a simple automatic device having for its motive power a spring which is caused to operate by the insertion of a coin into the coin-chute of the machine, as shown in the drawings and more 25 fully described hereinafter.

In the accompanying drawings, Figure 1 illustrates an end elevation, partly in section, of an instrument embodying the principle of my invention. Fig. 2 is a sectional view on 30 the line 2 2 of Fig. 1, the top cover being removed and the standard supporting the instrument being omitted. Fig. 3 is a plan view of Fig. 2. Fig. 4 is a section on the line 4 4 of Fig. 2. Fig. 5 is a detached sectional view on the line 5 5 of Fig. 6. Fig. 6 is a detached sectional view on the line 6 6 of Fig. 35 7. Fig. 7 is a section on the line 7 7 of Fig. 6, and Fig. 8 is a detached perspective view of the mechanism controlled by a coin for 40 starting and stopping the instrument.

Similar letters of reference refer to similar parts throughout the drawings.

A is the record, in the form of a disk having upon its face a layer of wax or other like 45 material upon which sound-waves have been recorded.

B is a rotatable table carrying the record, the same being held in position by a thumbscrew B'. The shaft C, which supports said 50 table, has suitable bearings in the framework

D of the motor, and motion is imparted to said shaft as follows:

A beveled pinion E on the shaft C engages a beveled gear E', loosely supported upon the shaft E². On the same shaft is loosely hung 55 a pinion E³, connected by a sleeve to the beveled gear E', which meshes with a gear-wheel E⁴, fixed to a shaft E⁵, and upon this same shaft is fixed a pinion E⁶, which meshes with a gear-wheel E⁷, loosely hung to the shaft E². 65

The spring E⁸ is secured at one end to the shaft E², the outer end being connected to the gear-wheel E⁷ by a pin e⁷. Upon the shaft E² is also secured a ratchet-wheel E⁹, having a pawl e⁹ engaging it, which is pivoted to the 65 framework of the motor. In winding the spring E⁸ the shaft E² is turned by a crank E¹⁰. (Shown in dotted lines in Fig. 1.)

The sound-box F of the instrument comprises a casing F' and ring F², between which 70 is secured the diaphragm F³. The reduced portion f' of the casing is provided with a flexible tube F⁴, through which the sound-waves are conveyed to a coupling f⁴ in the cover and thence through the tube F⁵ to the 75 earpieces.

The stylus or needle G is mounted in a binding-post G', provided with a set-screw G³, the same being secured to a spring-plate G³, which is fastened to the sound-box by screws 80 g g, the spring-plate G being connected to the diaphragm F³ by a pin f³ in the usual manner, and in some cases an additional spring-plate G⁴ may be employed, provided with an adjusting-screw g⁴. 85

Secured to and forming part of the sound-box is a short arm H, connected to the saddle I by means of screws h h, and in order to provide for a slight irregularity which I find will at times occur between the feed imparted to 90 the saddle and that imparted to the stylus by the record I provide a slot h' in the arm H, in which one of the screws h is free to play.

The saddle I is sleeved at its upper end to a bar J, which bar is supported by uprights 95 K and K', connected to and forming part of base-plate K². The saddle I is caused to travel backward and forward upon the bar J by means of two screws L and L'. The former, when engaged with the threaded portion of 100

the saddle I', will impart a slow movement corresponding to that imparted to the stylus or needle by the groove in the record-plate, the latter screw imparting a quick-return 5 movement to the stylus after the same has been lifted from the face of the record.

The motive power for operating the screws L and L' is conveyed from the shaft C to the shaft M by means of pulleys C' and M', connected by a belt M². The shaft M is provided with a worm M³, which engages the teeth of the worm-wheels L² and L³, secured, respectively, to the ends of the worms L and L'.

The movements given to the saddle and 15 sound-box carried thereby through the arm H are as follows: When the saddle is in the position shown in Figs. 3 and 5, the semi-threaded portion I' is in engagement with the worm L, which conveys the saddle forward 20 until the same is brought in contact with the cam N, and a further movement compresses the spring n and brings the toothed portion of the cam into contact with a collar O, which is fixed to the worm-shaft, the same having 25 corresponding teeth which engage the toothed portion of the cam. The cam now turns with the screw-shaft, and a pin i, projecting from the saddle, is acted upon by the cam and disengages the saddle from the screw L.

30 Suspended from the bottom of the saddle is a roller P, which when the saddle is in engagement with the screw L rests upon a track or guide Q. As the saddle is disengaged by the cam N from the screw L the roller, which 35 has considerable vertical play upon the pin which secures it to the saddle, drops by gravity down behind the track or guide Q as the saddle is shifted and holds the saddle and pin I², projecting therefrom, into engagement with 40 the quick-return worm L'.

In order that the pin I² will properly engage the thread of the screw L' when the saddle is shifted, I provide a spring S, which is located in an opening directly back of the pin, 45 so that in case the pin strikes the thread at the moment the saddle is shifted the spring will be compressed until the pin is properly adjusted between the coils of the thread.

As the saddle is moved along by the worm 50 L' the roller P is brought in contact with the inclined plane R, which raises said roller from the track or guide Q, and the weight of the sound-box shifts the saddle out of engagement with the worm L' and into engagement 55 with the worm L.

The governor T is of the ordinary centrifugal type, comprising the weighted arms T' and T², connected to the sleeve T³ by connecting-links T⁴ and T⁵, a spring S² being interposed 60 between the upper pivotal and fixed connection for the arms T' and T² and the loosely-supported flanged sleeve T³. The shaft T⁶, which carries the governor, is driven from the shaft C by means of a belt T⁷ and pulleys T⁸ 65 and T⁹. The speed of the machine is regulated by a plate U and thumb-screw u², the former being pivoted at a point u and pro-

vided with a pad u', which bears against the flanged portion of the sleeve T to a greater or less extent as the governor revolves, and governs the speed of the device by the frictional contact between said parts.

The coin mechanism for controlling the operation of the instrument embraces a lever V, which is pivoted at a point v, the weight of 70 said lever and its connecting parts being counterbalanced by a spring S³. An arm V' projects out some distance from the lever V and normally engages a projection w on the disk W, which latter is secured to and rotated by 75 the shaft M. Carried by the lever V is a bar V², acted upon in one direction by a spring S⁴, so as to cause one end of the bar to lie in the path taken by the coin in the chute X. When a coin is inserted into the chute X, it passes 80 along until it comes in contact with the projecting end of the bar V², the weight of the coin being sufficient to bear down the lever V against the action of the spring S³, which disengages the arm V from the projection w on 85 the disk W. The instrument being free to operate, the saddle I is fed slowly forward by the screw L, the roller P coming in contact at or near the end of its travel with a lever Y, which, being connected to the lever Y' by a 90 small shaft y, operates the bar V² against the action of the spring S⁴ and releases the coin. The coin being released from the bar V², the spring S³ comes into action and returns the lever V to its normal position; but as the 95 roller V³ at this point has been carried forward by the bar V² in releasing the coin the roller V³, upon the return of the lever V, comes in contact with a stop V⁴, which prevents the arm V' from engaging and locking the disk W 100 until the saddle I has been reversed by the screw L and carried a distance sufficient to disengage the lever Y and allow the spring S⁴ to return the bar V² to its initial position.

Having now described my invention, what 110 I claim, and desire to secure by Letters Patent, is—

1. In a gramophone, a record-disk mounted upon a vertical shaft, a sound-box provided with a stylus operated upon by the record, a spring means for rotating said record, a device connected with and adapted to guide the sound-box, said device being supported so as to be capable of traveling across the face of the disk, a screw connected with the source 115 of power and adapted to engage with said device and automatically impart to it and the sound-box a slow positive motion in one direction across the disk, a second screw adapted to engage with said device and automatically 120 impart to it a quick positive motion in the opposite direction and a cam for shifting said device from one to the other of said screws.

2. In a gramophone, a record-disk, spring means for rotating the same, a sound-box provided with a diaphragm and stylus operated upon by the record, a short arm connected to the sound-box and guided by a bar supported by the framework of the machine, a screw 125

connected to the source of power and adapted to convey the sound-box and its connections with a slow motion across the face of the disk in one direction, a second screw connected 5 with the source of power and adapted to convey the sound-box and its connections with a quick motion in the opposite direction, and a cam mounted upon one of said screws for transferring the arm carrying the sound-box 10 from one to the other of said screws.

3. In a gramophone, a record-disk mounted upon a table supported upon a vertical shaft, spring means for rotating said shaft, a sound-box provided with a diaphragm and stylus 15 operated upon by the record, a short arm connected to the sound-box and fulcrumed to a suitable bearing upon a horizontal bar which is supported by the framework of the machine, a screw connected to the source of 20 power and adapted to convey the sound-box and its connections with a slow motion across the face of the disk in one direction, a second screw connected to the source of power and adapted to move the sound-box and its connections with a quick motion in the opposite 25 direction, and a cam carried by the first-mentioned screw for transferring the arm carrying the sound-box from one to the other of the screws.

30 4. In a gramophone, a record-disk suitably supported upon a vertical shaft, spring means for rotating said shaft, a sound-box provided with a diaphragm and stylus operated upon by the record, a short arm connected to the sound-box and having a bearing fulcrumed to a saddle upon a bar which is supported by the framework of the machine, a screw connected to the source of power and adapted to convey the saddle and its connections across 35 the face of the disk in one direction, a second screw connected to the source of power and adapted to move the saddle and its connections in the opposite direction, a cam operated by the first-named screw for transferring 40 45 ring the arm carrying the sound-box from one to the other of said screws, a coin-chute, a pivoted lever, one end of which is in line with said coin-chute and adapted to be acted upon by a coin so as to unlock the operating mechanism.

50 5. In a gramophone, a record-disk mounted upon a table supported upon a vertical shaft, spring means for rotating said shaft, a sound-box provided with a diaphragm and stylus operated upon by the record, a short arm con-

nected to the sound-box and having a suitable bearing upon a horizontal bar which is supported by the framework of the machine, a screw connected to the source of power and adapted to convey the sound-box and its connections with a slow motion across the face of the record-disk in one direction, a second screw connected to the source of power and adapted to move the sound-box and its connections with a quick motion in the opposite 60 direction, means for transferring the arm carrying the sound-box from one to the other of the screws, a coin-chute, a pivoted lever one end of which is in line with said coin-chute and adapted to be acted upon by a coin so as 65 to unlock the operating mechanism.

6. In a gramophone, a record-disk mounted upon a rotatable table, spring mechanism for operating the same, a sound-box provided with a diaphragm and stylus which is adapted 70 to traverse across the face of the record, a screw for conveying the sound-box in one direction with a slow motion, a screw for conveying the sound-box in the opposite direction, and a cam mounted upon one of said 75 screws, the same being adapted to shift the parts carrying the sound-box out of engagement with one and into engagement with the other of the said screws.

7. In a gramophone, a record-disk mounted 80 upon and detachably secured to a rotatable table which is supported and carried by a vertical shaft, spring means as shown and described for operating said shaft, a sound-box provided with a diaphragm and stylus operated upon by the record, an arm connected 85 with and adapted to guide the sound-box, a saddle having a yielding connection with said arm and being sleeved to a horizontal rod suitably supported at its ends, a screw for 90 operating said saddle with a slow motion in one direction, a cam as shown and described for disengaging said saddle at the end of its travel, a screw adapted to impart a quick motion to the saddle in the opposite direction, 95 means as shown and described for keeping said saddle in contact with the last-mentioned screw and releasing the same therefrom at 100 the end of its travel.

In testimony whereof I affix my signature 105 in presence of two witnesses.

JOSEPH W. JONES.
